UNITED STATES PATENT OFFICE.

GREGORY J. SPOHRER, OF EAST ORANGE, NEW JERSEY, ASSIGNOR TO THE MOTOR-COMPRESSOR COMPANY, A CORPORATION OF DELAWARE.

STARTING MECHANISM FOR INTERNAL-COMBUSTION ENGINES.

1,376,838.

Specification of Letters Patent.

Patented May 3, 1921.

Application filed September 21, 1918. Serial No. 255,063.

To all whom it may concern:

Be it known that I, GREGORY J. SPOHRER, a citizen of the United States, residing at East Orange, in the county of Essex, State 5 of New Jersey, have invented certain new and useful Improvements in Starting Mechanism for Internal-Combustion Engines; and I do hereby declare the following to be a full, clear, and exact description of the 10 invention, such as will enable others skilled in the art to which it appertains to make and use the same.

This invention relates to mechanism for starting internal combustion engines manually, and is directed to the provision of a 15 manual starting mechanism of an improved form which is simple in construction, which may be manufactured at low cost, and with which injury to the operator resulting from 20 a back kick of the engine is effectually guarded against.

A manual starting mechanism for an internal combustion engine should be normally disconnected from the engine shaft, 25 should be capable of ready connection to the engine shaft, should be disconnected from the engine shaft automatically when the engine starts to operate under its own power, and should be provided with devices for 30 effecting substantially instant release of the starting mechanism from the engine shaft in event of a back-kick of the shaft which otherwise might cause injury to the operator. A mechanism constructed in accordance 35 with this invention fulfills all of the foregoing requirements and is of such simple construction that it is reliable in operation, of little weight, may be manufactured at low cost, and is of special utility in connection 40 with internal combustion engines for propelling aircraft. The feature of the invention of primary importance is the provision of a pawl and ratchet mechanism for connecting the hand crank to a starting 45 shaft and a multiplicity of releasing devices arranged at intervals about the axis of the starting shaft, each of which is capable of effecting disconnection of the hand crank from the starting shaft in event of a backward 50 movement of the hand crank caused by a back-fire of the engine.

The preferred embodiment of the invention is illustrated in the accompanying

drawings in which Figure 1 is a horizontal section of the starting apparatus; Fig. 2 is 55 an elevation of a portion of the apparatus; and Fig. 3 is a transverse section of the releasing device.

Referring to these drawings, 4 indicates the internal combustion engine which is to 60 be started. In Fig. 1, the apparatus is illustrated in the form in which it may be embodied for use on aeroplanes, the sides of the body of an aeroplane being indicated at 5. The shaft of the engine 4 is shown at 6, 65 the end of the shaft extending backwardly through the casing of the engine. This end of the shaft 6 is provided with a clutch member 7 of any suitable construction. In axial alinement with the shaft 6 is a short 70 shaft 8 mounted for rotation in a bearing 9. The end of the shaft 8 is provided with one or more spiral threads 10 and on this end of the shaft is a clutch member 11, the 75 inner surface of which is provided with one or more spiral grooves in which the threads 10 are received, so that relative rotation of the shaft 8 and member 11 causes axial movement of the clutch member 11 into and out of engagement with the clutch member 80 7. The bearing 9 for the shaft 8 is provided with a tubular extension 12 which telescopes with a tubular extension 13 mounted upon the crank case of the engine 4. On the interior of the sleeve 13 is a leaf 85 spring 14, the free end of which is in frictional engagement with the surface of the clutch member 11, the purpose of this spring being to offer a small frictional resistance to the rotation of the clutch member 11 so 90 as to insure that the clutch member will not rotate with shaft 8 when such rotation is not desired.

At the opposite end of the shaft 8 is a bevel gear 15 which is in mesh with a bevel 95 pinion 16 fixed upon a shaft 17 which is shown as extending transversely of the body of the aeroplane and mounted for rotation in bearings 18 and 19 which are secured to sides 5 of the body.

At one end, the shaft 17 passes through the bearing 19 and has a ratchet wheel 20 keyed to it, the ratchet wheel being shown in Fig. 2 as provided with two ratchet teeth. Loose on the end of the shaft 17 is a hand 105 crank 21 held in position by a collar 22,

This hand crank has a disk 23 secured to it and 2 pawls 24 are pivotally mounted upon the face of the disk 23 in position to coact with the teeth of the ratchet wheel 20, each 5 pawl 24 being provided with a spring 24' for pressing it yieldingly toward the teeth of the ratchet.

The portion of the bearing 19 on the outer side of the side plate 5 is in the form of a 10 disk and this disk has a multiplicity of notches or slots cut in its periphery at equal distances apart. As shown in Fig. 3, there are eight of these slots. In each of these slots is a releasing device for effecting the 15 release of a pawl 24 from engagement with a tooth of ratchet wheel 20. Each of these releasing devices 25 is in the form of a block of metal fitting snugly within its slot and projecting at one end beyond the face of 20 the disk. Preferably each of the releasing devices is pivotally mounted at one end as shown at 26. Means are provided for holding the several releasing devices 25 yieldingly in the positions in which they are 25 shown in Figs. 1 and 3. This means preferably consists of a spiral spring in the form of a ring 27 lying in a circumferential groove in the disk portion of the bearing member 19, this groove being of such depth 30 that the spring lies in contact with the outer faces of the several releasing devices 25.

The portion of each of the releasing devices 25 extending beyond the face of the disk on the bearing member 19 is in the form 35 of a cam as shown at 28 in Fig. 3, its opposite faces being inclined at an angle of substantially 45° to a radius passing through the cam. Each of the pawls 24 is provided with a projection 29 on one side thereof 40 which is also in the form of a cam having sides inclined to a radius and which is adapted to rotate as the handle 21 is rotated in a plane transverse to the shaft 17 which includes the cams 28 of the releasing devices. 45

In order to start the engine, the operator grasps the handle 21 and turns it, thereby rotating the shaft 17 and the shaft 8 to which it is connected by the bevel gears 15 50 and 16. The rotation of shaft 17 is effected by the engagement of the pawls 24 with teeth on the ratchet 20, the pawls being moved into engagement with the ratchet by the springs 24' and the ratchet being keyed 55 to the shaft 17. When the shaft 8 is so rotated it turns relatively to the clutch member 11 as rotation of the latter is resisted by the pressure of the spring 14. Therefore, the clutch member 11 is moved axially upon 60 the shaft 8 until it is carried into engagement with the clutch member 7 on the engine shaft 6. Thereafter the engine shaft is rotated with the shaft 8 to start the engine. As soon as the engine starts to operate 65 under its own power, the rotation of the

shaft 6 causes rotation of the clutch member 11 at a speed in excess of the speed of rotation of shaft 8, and the coacting spiral threads and grooves cause the clutch member 11 to be moved back upon the shaft 8 until 70 it is carried out of engagement with the clutch member 7.

When the handle 21, disk 23 and pawls 24 are so rotated to start the engine, the forward sides of the outer ends of the cam 75 projections 29 on the pawls engage in succession the rearward sides of the inner ends of the cam projections 28 on the releasing devices 25. The free ends of the releasing devices 25 are thus raised slightly against 80 the tension of their spring 27 one after another and serve to reinforce the holding-on action of the springs 24', maintaining pawls 24 in connecting position. In event of a 85 back-fire of the engine causing a backward rotational movement of the shaft 17, ratchet 20, pawls 24 and handle 21, the rearward sides of the outer portions of the projections 29 on the pawls 24 engage the forward sides 90 of the inner ends of the projections 28 on the releasing devices 25 and instead of the releasing devices being raised against the tension of their spring by the cam projections 29 on the pawls, the cam projections 29 and the pawls are turned about their pivots 95 against the tension of their springs 24' by the cam projections 28 on the releasing devices 25 to lift the teeth of the pawls out of engagement with the teeth of the ratchet 20. This effects substantially instant disconnection of the handle 21 from the 100 shaft 17.

It will be noted that there are eight of the releasing devices located equidistant about the axis of shaft 17 and that any pair of 105 the releasing devices may serve to lift the pawls and thus disconnect the handle from the engine. Therefore, backward rotation of the handle occasioned by a back-fire of the engine may extend through not more 110 than one-eighth of a revolution of the handle. As many of the releasing devices may be provided as desired so as to reduce to any desired amount the possible backward movement of the handle occasioned by 115 a back-fire of the engine before the handle is released from its connection to the engine shaft.

Particular attention is directed to the simplicity of the construction of the parts provided for effecting the release of the handle in the case of a back-fire. The additional parts provided for this purpose consist merely of a disk with slots in its periphery releasing devices located in these slots, a 120 single spring for positioning all of the releasing devices, and cam projections on the pawls coacting with cams formed on the 125 ends of the releasing devices. The mechanism may, therefore, be constructed at low 130

cost and it is of such simplicity as to minimize the danger of faulty operation and breakage or displacement of essential parts.

I claim:

5. Mechanism for starting internal combustion engines comprising a starting member, a ratchet and pawl for connecting the starting member to the engine shaft, and a plurality of releasing devices located about 70 the axis of the ratchet and pawl mechanism and successively moved by the different pawls and each of them adapted to coact with the ratchet and pawl mechanism to disconnect the pawl from the ratchet on 75 backward movement of the starting member.
10. Mechanism for starting internal combustion engines comprising the combination of a starting member, a pawl and ratchet mechanism for connecting the starting member 80 to the engine shaft, a cam on the pawl and a multiplicity of releasing devices located about the axis of the ratchet and each provided with a cam for coaction with the cam on the pawl, the releasing devices being 85 adapted to be moved successively by the pawl when the starting member is rotated in one direction and the pawl being adapted to be moved by any one of the releasing devices when the starting member 90 is rotated in the opposite direction.
15. Mechanism for starting internal combustion engines comprising the combination of a starting member, a pawl and ratchet for connecting the starting member to the 95 engine shaft, a plurality of releasing devices located about the axis of the pawl, a single spring for holding all of the releasing devices yieldingly in position, and coacting cam surfaces on the pawl and the 100 releasing devices whereby the releasing devices are moved successively by the pawl against the tension of their spring when the starting member is rotated in one direction and the pawl is moved by any one of the 105 releasing devices when the starting member is rotated in the other direction.
20. Mechanism for starting internal combustion engines comprising the combination of a starting member, a pawl and ratchet for connecting it to the engine shaft, a disk adjacent to the pawl having a plurality of slots in its periphery arranged about the 110 axis of the ratchet, a releasing device in each of the slots in the disk, a cam on the shaft normally driven by the first clutch member and driving said first clutch member upon reverse movement of said second clutch member, disconnectible cranking means for said starting shafting and means interposed 115 between the same and the starting shafting displaced during driving of the starting action but rigidly positioned upon the reverse movement of the driving action and thereby disconnecting the cranking means from the 120 starting shafting.
25. Mechanism for starting internal combustion engines comprising the combination of an engine shaft, starting shafting, a clutch member movable longitudinally thereof, a clutch member on the engine 125 shaft normally joining the engine shaft and starting shafting, which is shifted on the starting shafting by the engine shaft upon movement thereof, cranking means, means at another end of the starting shafting for connecting 130
30. Mechanism for starting internal combustion engines comprising the combination of an engine shaft, a clutch member thereon, a starting shaft in alinement with the engine shaft, a clutch member movable axially upon the starting shaft and connected thereto by a spiral thread, a handle for actuating the starting shaft connected thereto by a ratchet and pawl mechanism, and a multiplicity of releasing devices arranged 75 about the axis of the ratchet and adapted to be moved successively by the pawl when the handle is turned in one direction and any one of them adapted to move the pawl out of engagement with the ratchet when 80 the handle is moved in the opposite direction.
35. Mechanism for starting internal combustion engines comprising the combination of an engine shaft, a clutch member thereon, a starting shaft, a clutch member movable axially thereon and connected thereto by spiral threads, a handle, a pawl and ratchet for connecting the handle to the starting shaft, a disk adjacent to the pawl 90 provided with a plurality of slots about the axis of the disk, a releasing device located in each of said slots, means for yieldingly positioning the releasing devices, a cam on each releasing device, and a cam on the 95 pawl movable in the path of the cams on the releasing devices, the releasing devices being adapted to be moved by the cam on the pawl against the tension of said yielding positioning means when the handle is 100 rotated in one direction and the pawl being adapted to be moved out of engagement with the ratchet by any one of the releasing devices when the handle is rotated in the opposite direction.
40. Mechanism for starting internal combustion engines comprising the combination of a starting member, a pawl and ratchet for connecting the starting member to the 105 engine shaft, a plurality of releasing devices located about the axis of the pawl, a single spring for holding all of the releasing devices yieldingly in position, and coacting cam surfaces on the pawl and the 110 releasing devices whereby the releasing devices are moved successively by the pawl against the tension of their spring when the starting member is rotated in one direction and the pawl is moved by any one of the 115 releasing devices when the starting member is rotated in the other direction.
45. Mechanism for starting internal combustion engines comprising the combination of a starting member, a pawl and ratchet for connecting it to the engine shaft, a disk adjacent to the pawl having a plurality of slots in its periphery arranged about the 120 axis of the ratchet, a releasing device in each of the slots in the disk, a cam on the shaft normally driven by the first clutch member and driving said first clutch member upon reverse movement of said second clutch member, disconnectible cranking means for said starting shafting and means interposed between the same and the starting shafting displaced during driving of the starting action but rigidly positioned upon the reverse movement of the driving action and thereby disconnecting the cranking means from the starting shafting.
50. Mechanism for starting internal combustion engines comprising the combination of an engine shaft, starting shafting, a clutch member movable longitudinally thereof, a clutch member on the engine 125 shaft normally joining the engine shaft and starting shafting, which is shifted on the starting shafting by the engine shaft upon movement thereof, cranking means, means at another end of the starting shafting for connecting 130

the cranking means and the starting shafting, and means for disconnecting the connecting means, said disconnecting means reinforcing the connecting means during starting action.

9. Mechanism for starting internal combustion engines comprising the combination of a starting shafting, cranking means, a connecting member between said starting shafting and said cranking means, and a releasing device interposed in the path of said connecting member at all times and normally deflected thereby, and in turn in case of back-firing deflecting the connecting member, and automatically disconnecting the cranking means from the shafting upon reverse movement of the starting shafting.

10. Mechanism for starting internal combustion engines comprising the combination of an engine shaft, a starting shaft, a cranking means, a plurality of connecting means interposed between the cranking means and

the starting shaft, and releasing means passing over said connecting means during cranking, and passed under said connecting means upon reverse movement of the starting shaft.

11. Mechanism for starting internal combustion engines comprising the combination of an engine shaft, a starting shaft, a crank- 30 means, connecting members on the cranking means, and a plurality of releasing devices interposed in the path of the connecting members on the cranking means passing successively thereover and holding 35 the connecting members in position, said releasing devices being moved by the connecting members during the cranking action, and moving the connecting members out of connecting position upon a re-verse move- 40 ment of the starting and engine shafts.

In testimony whereof I affix my signature.

GREGORY J. SPOHRER.
